US00D625432S

(12) **United States Design Patent**
Guenev

(10) **Patent No.:** **US D625,432 S**
(45) **Date of Patent:** **** Oct. 12, 2010**

(54) **ENCLOSURE FOR BIOPHARMACEUTICAL PROCESSING EQUIPMENT**

(76) Inventor: **Guenko Guenev**, 116 Abby La., N. Kingstown, RI (US) 02852

(**) Term: **14 Years**

(21) Appl. No.: **29/355,838**

(22) Filed: **Feb. 15, 2010**

(51) **LOC (9) Cl.** 24-02

(52) **U.S. Cl.** D24/232

(58) **Field of Classification Search** ..... D10/81; D24/107, 158, 164, 165, 167, 170, 185–187, D24/231–233, 108, 217; 73/864.01, 864.12; 134/21, 22.11, 24, 26–27, 169 R; 422/62–64, 422/99, 100; 436/47, 49, 179, 180; D13/162–163; 600/300, 301, 368, 372, 481, 529, 544, 554, 600/561

See application file for complete search history.

(57) **CLAIM**

The ornamental design for enclosure for biopharmaceutical processing equipment, as shown and described.

DESCRIPTION

FIG. 1 is a front perspective view of the enclosure for biopharmaceutical processing equipment, showing the new design; the portions shown in broken lines form no part of the claimed invention;

FIG. 2 is a rear perspective view of the enclosure for biopharmaceutical processing equipment, showing the new design; the portions shown in broken lines form no part of the claimed invention;

FIG. 3 is a front view thereof; the portions shown in broken lines form no part of the claimed invention;

FIG. 4 is a rear view thereof; the portions shown in broken lines form no part of the claimed invention;

FIG. 5 is a left view thereof; the portions shown in broken lines form no part of the claimed invention;

FIG. 6 is a right view thereof; the portions shown in broken lines form no part of the claimed invention;

FIG. 7 is top view thereof; the portions shown in broken lines form no part of the claimed invention; and,

FIG. 8 is a bottom view thereof; the portions shown in broken lines form no part of the claimed invention.
